UNITED STATES PATENT OFFICE

2,458,632

IONIZATION CHAMBER

J Howard Parsons, Oak Ridge, Tenn., assignor to
the United States of America as represented by
the United States Atomic Energy Commission

Application December 11, 1945, Serial No. 634,315

4 Claims. (Cl. 250—83.6)

1

This invention relates to an arrangement for reducing losses in high frequency electrical circuits and more particularly to circuit arrangements for transmitting high frequency pulses with a minimum of attenuation.

In apparatus such as parallel plate ionization chambers and concentric conductors which furnish relatively high frequency pulses to amplifying equipment the input impedance increases with the frequency which results in greater attenuation of the high frequency components than of the low frequency components.

An object of the invention is to provide an ionization chamber so constructed that it will provide a low impedance input when connected to an electronic counting circuit.

Another object of the invention is the provision of a capacity guard for an ionization chamber, a concentric cable and the like.

Another object of the invention is the provision of a circuit arrangement whereby an apparatus with a capacity guard may be connected to an amplifying circuit in a manner to minimize attenuation of high frequency pulses.

Other objects and advantages of the invention will become evident from the following description when read in connection with the accompanying drawing in which

Fig. 1 is a schematic wiring diagram showing a prior art ionization chamber and measuring circuit;

Fig. 2 is an equivalent circuit representative of the circuit of Fig. 1;

Fig. 3 is a partial view in perspective and with parts torn away of an ionization chamber incorporating the invention;

Fig. 4 is a schematic wiring diagram showing the chamber of Fig. 3 connected to an electrometer;

Fig. 5 is an equivalent circuit representative of the circuit of Fig. 4; and

Fig. 6 shows in perspective a cable constructed and connected in accordance with the invention.

Referring to Fig. 1 there is shown a conventional type of ionization chamber having two parallel plates 10 and 11 comprising, respectively, a high voltage electrode and a collecting electrode, and surrounded by a grounded outer cylindrical shell 12. The collecting electrode 11 is connected to the grid 13 of a vacuum tube 14

2

having a grid resistor 15 and a cathode resistor 16. The normal input circuit just described can be resolved roughly into the equivalent circuit shown in Fig. 2 in which

5. e_i is the theoretical voltage pulse available
 R_c is the equivalent chamber resistance
 C_1 is the capacity of the collecting electrode to ground
10 R_1 is the grid resistor 15, and
 e_o is the signal to the grid 13.

Since input capacity of the tube 14 may be neglected in a cathode follower circuit

$$e_o = e_i \frac{Z_g}{Z_g + R_c}$$

Where Z_g is the resultant impedance of the grid circuit and equals

$$\frac{1}{R_1 \frac{1}{2\pi f C_1} + \frac{1}{R_1 + 2\pi f C_1}}$$

20 Since R_1 must be very large, Z_g will depend on frequency components of the pulses and high frequency components are attenuated more than low frequency components. Such attenuation is not desired.

In accordance with the present invention as embodied in Figs. 3 and 4 a capacity guard in the form of a hollow cylinder 17 surrounding the electrodes 10 and 11 and inside the grounded shell 12 is provided to reduce high frequency losses as hereafter described. This capacity guard 17 when connected to the cathode of the tube 14 renders the input impedance substantially resistive and thus not frequency discriminative. This will be evident from a consideration the equivalent circuit of Fig. 4 shown in Fig. 5.

30 In Fig. 5 the terms employed are the same as those of Fig. 2 except that

C_1 is the capacity between the collecting electrode 11 and the guard 17.

35 C_k is the capacity between the guard 17 and ground and R_k is the cathode resistor 16.

40 It will be seen that the capacity between the collecting electrode 11 and shell 12 is negligible because of the presence of guard 17. Thus with the capacity guard 17 connected to the cathode of the cathode follower tube 14 and with the resistor 16 (R_k) small in value, the impedance of

the cathode circuit remains nearly constant within the frequency band ordinarily encountered in ionization chambers. Additionally, e_0 remains nearly constant since for small changes of R_k the gain is practically constant.

From the above it will be seen that the provision of a capacity guard connected to the cathode follower circuit considerably reduces the high frequency component losses in an ionization chamber and reduces resolution loss.

The use of a capacity guard as above described is not restricted to ionization chambers but may be employed generally in electrical apparatus where it is desired to minimize high frequency losses such as, for example, in a cable as shown in Fig. 6 where instead of the usual tubular conductor enclosing a central rod or wire, a central conductor 18 is surrounded by two spaced concentric conductors or conducting sheaths 19 and 20, there being insulation between the sheaths 19 and 20 and between conductor 18 and sheath 19 as shown. In this arrangement a cathode follower circuit is employed with the central conductor 18 connected to the grid of a tube 21 and the intermediate sheath or conductor 19 connected to the cathode of the tube 21, the outer tubular sheath or conductor 20 being grounded.

While for the purpose of explaining the invention, two particular embodiments have been described, it is to be understood that many modifications will be apparent to those skilled in the art and all such modifications are intended to be included in the scope of the appended claims.

I claim:

1. An ionization chamber comprising a pair of parallel plate electrodes spaced in confronting relationship, a hollow cylindrical electrically conductive member surrounding the interelectrode space of said electrodes, a second hollow cylindrical electrically conductive member surrounding said first-mentioned hollow cylindrical member and being grounded, and an electronic amplifying circuit having a cathode follower circuit,

the cathode being connected to said first-mentioned hollow cylindrical member.

2. An ionization chamber comprising an outer shell, a pair of plate electrodes spaced in parallel relation within the container, and a ring guard of conducting material insulated from and positioned between the outer shell and said electrodes and forming a shield between said electrodes and outer shell.
3. In an ionization chamber having spaced electrode members one of which is a collecting electrode, a casing of electrically conductive material around said electrodes, the casing being grounded, and an electronic amplifying circuit having its input coupled to said collecting electrode, the improvement which comprises an additional electrical shielding member interposed between said collecting electrode and said casing around said collecting electrode and said additional electrical member having a connection to the cathode of said amplifying circuit.
4. The structure of claim 3 wherein the amplifying circuit is of the cathode follower type.

J HOWARD PARSONS.
